CLAIM

The ornamental design for dental pliers, as shown and described.

DESCRIPTION

FIG. 1 is a top and side perspective view of dental pliers showing my new design;

FIG. 2 is a top perspective view thereof;

FIG. 3 is a side elevation thereof;

FIG. 4 is a side elevation of the side opposite that shown in FIG. 3;

FIG. 5 is an end elevation thereof; and,

FIG. 6 is an end elevation of the end opposite that shown in FIG. 5.

The broken lines shown in the drawings represent environmental structures and are included for the purpose of illustration and form no part of the claimed design.
